[57] **CLAIM**

The ornamental design for a scratch guard for automobile doors, as shown and described.

DESCRIPTION

FIG. 1 is a front elevational view of a scratch guard for automobile doors showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The diagonal lines in FIG. 1 of the drawing are understood to represent a surface pattern.
